United States Patent Office.

JACOB G. JONES, OF BALTIMORE, MARYLAND.

Letters Patent No. 94,829, dated September 14, 1869.

IMPROVED SASH-BALANCE.

The Schedule referred to in these Letters Patent and making part of the same.

To all whom it may concern:

Be it known that I, JACOB G. JONES, of the city and county of Baltimore, and State of Maryland, have invented a new and improved Sash-Balance; and I do hereby declare that the following is a full, clear, and exact description of the construction and operation of the same, reference being had to the accompanying drawings, making a part of this specification, in which—

Figure 1 is a section, through line $x x$ of fig. 2.

Figure 2 is a rear view.

This invention consists in the use, in connection with the usual spring-device for balancing sashes, of an adjusting-device, whereby the tension of the spring can be varied to suit the different sizes of sashes to be balanced.

In the drawings—

- a* is the lower-sash cord;
- b* is a guide-pulley, over which it runs;
- c* is a spool-pulley, on which it winds;
- d* is the shaft of pulley *c*;
- e* is a small pinion on shaft *d*;
- f* is a stationary shaft or rod, parallel to shaft *d*;
- g* is a large pinion running loosely on shaft *f*, and gearing with pinion *e*;
- h* is a disk, parallel to wheel *g*, and also running loosely on shaft *f*;
- i i i* are rods connecting disk *h* to wheel *g*;
- k* is a spring coiled around and attached to shaft *f*,

inside of the rods *i i i*, and at its outer end attached to one of said rods; and

J is the casing or supporting-plate of the apparatus, all being constructed and arranged as shown in the drawings.

For the upper-sash cord, a duplicate of the above-described apparatus is arranged in the same casing or housing, which is made in the proportions and form shown, for that special purpose.

The end of shaft *f* may project through the supporting-plate, and be squared off, so that a key will fit upon it, by which the shaft can be turned, so as to adjust the tension of spring *k* to any degree required.

The whole apparatus is simple, cheap, and compact, and can be applied to any style of sash.

I am aware that it is not new to balance window-sashes by means of clock and other springs, and I do not wish to be understood as laying claim to such invention; but

Having fully described my invention,

What I do claim as new, is—

The sash-balance herein described, consisting essentially of the adjustable shaft *f*, gear-wheel *g*, spring *k*, shaft *d*, pinion *e*, and pulleys *b*, all constructed, arranged, and operating in the manner and for the purpose specified.
